UNITED STATES PATENT OFFICE.

JAMES V. GERAGHTY, OF NEW YORK, N. Y.

METHOD AND APPARATUS FOR SANDING RAILS.

1,136,667.

Specification of Letters Patent.

Patented Apr. 20, 1915.

Application filed June 19, 1914. Serial No. 846,042.

To all whom it may concern:

Be it known that I, JAMES V. GERAGHTY, a citizen of the United States, residing in the borough of Manhattan, city, county, and State of New York, have invented certain new and useful Improvements in Methods and Apparatus for Sanding Rails, of which the following is a specification, reference being made therein to the accompanying drawings.

My invention relates to methods and apparatus for sanding rails, particularly the rails of an electrically operated railway system.

The object of my invention, among other things, is the provision of a novel method of distributing sand along the upper surface of the rails, thereby preventing and removing what are commonly known as rail corrugations. These corrugations are produced in shallow waves upon the tread of the rails of the railway by the wheels of the cars which pass over them; they are very prevalent on electric railways and tramways, under varied conditions. The origin and resulting causes of corrugation are difficult of determination, and many theories have been advanced to prevent same, or to remove corrugations already existing. It is generally understood that corrugations occur where slipping takes place, for it has been generally found that corrugations take place where the electric current to operate the car is acting at full power.

Many theories have been advanced for preventing, and for removing corrugations already existing and though my discovery may be practised by several different mechanisms or machines now in use, those skilled in the art have failed to discover certain new and useful improvements practised in my invention.

The characteristic feature of my present invention is the method or process of doing away with those corrugations, occurring on electric railways, which consists in the supplying of sand between the rapidly revolving wheels of the car and the rail, automatically regulated by the advance of the control while bringing the car to speed, but not operated when the current is being cut out; simultaneously advancing the control, bringing the car to speed, distributing sand, availing myself of the ability of the sand so distributed to cut the surface of the crests, also availing myself of the ability of

the pressure of the rapidly moving wheels to smooth out the cut surface and simultaneously furnishing the requisite adhesion under the various wheels which may be passing over non-corrugated rail surface, to prevent undesirable intermittent slipping and hold the wheels to the rail, thus doing away with the formation of other corrugations.

In order to present a full understanding of my present invention I have shown and described a complete automatic sanding apparatus by means of which the method hereinbefore described may be practised. It is to be clearly understood however that my improved method is not limited to the apparatus herein described, but other forms, or combinations, may be constructed whereby my improved method of sanding rails to do away with corrugations is accomplished.

In the accompanying drawings, Figure 1 is a view partly in section taken on the line *a—a'* of Fig. 2. Fig. 2 is a side elevation of a car and wheel with my device attached. Fig. 3 is a view partly in section of the valve for regulating the flow of the sand. Fig. 4 is a detailed view of the controller partly in section. Fig. 5 is an enlarged detailed view taken on the line *b—b'* of Fig. 4. Fig. 6 is a diagrammatic view of my improved apparatus.

Similar numerals refer to similar parts throughout the several views.

Referring to Figs. 1 and 2, 7 represents sand boxes suitably located in the car 8 over the wheels 9. The wheels 9 which are mounted on the axle 10 ride on the rails 11. Beneath each sand box are two passages formed in the collars 12 secured to the under side of the floor of the car 8 as shown in Figs. 1 and 2, in which are located the slide valves 13; the outer end of each valve 13 is pivotally secured at 14 to the solenoids 15. The coil spring 16 normally closes the valve 13 as shown in Fig. 3. 17 are sand pipes provided with funnels 18, two for each wheel as shown in Fig. 2, so arranged to distribute sand in proximity to the point of contact between the tires of the wheels 9 and the rails 11. The same construction and parts are employed for each of the wheels 9 of the car.

Referring to Figs. 4 and 5, 19 represents a controller having attached thereto the transverse roller 20 suitably insulated as shown in Fig. 4, and having a notched out

slot 21 in the upper portion thereof, through which slot the pin 22 passes as the roller revolves. The roller 20 is insulated at 23, and is conductive at 24 as shown in Fig. 5, 5 and these portions are so arranged to rotate over the contact plate 25 as shown in Figs. 4 and 5, the portion 23 on the backward movement of the controller 19, and the portion 24 on its forward movement. 26 is a 10 spring controlled pin at each end of the car adapted to be pressed down by the foot of the operator to make the necessary contacts, as shown in Fig. 6. 27 are contact buttons connected with the solenoids 15 as shown 15 in Fig. 6, and are adapted when the controller is moved to bring into operation such pairs of the solenoids 15 whereby the proper valves 13 are opened so as to allow sand to pass into the pipes 17 to distribute sand 20 along the surface of the rails 11, in the direction of the movement of the car.

In carrying out my process as the controller 19 is advanced, the roller 20 is rotated so as to remove the insulated portion 23 25 from the plate 25, but to have the portion 24 rest on this plate, thereby making contact between the plate 25 and the first push button 27 which operates the solenoids to open the valves to distribute sand along the rails. 30 As the controller is gradually advanced through the successive contact buttons 27, the hereinbefore described mechanism, successively operates the sanding device, as against the spring 16, with suitable relation 35 to the advance of the controller, whether in starting or in running positions, governed by the solenoid, and in direct proportion to the needs, thereby supplying the sand necessary to cause the requisite adhesion on the 40 various wheels, which supply is automatically regulated by the advance of the controller in bringing the car to speed, when the operator depresses the pin 26, shown in Fig. 6, to complete the electrical circuit.

45 As shown in Fig. 6, the solenoids 15 are connected by appropriate wiring with the main electric circuit for operating the motors attached to the axles 10 of the car. Alternate sets of solenoids are operated by 50 each of the controllers 19 according to the direction in which the car is moving as shown in Figs. 2 and 6, the object being to supply sand to each of the wheels 9 as it progresses along the track 11. For example, when the car is progressing to the right, the advance of the right hand controller 19 makes electrical connection between the first contact button 27, which has been connected with the main line circuit through the depression of the right-hand pin 26, and the contact plate 25 connected by proper wiring as shown in Fig. 6 with the first and third sets of solenoids 15, thereby opening the valves 13 to distribute sand along the rails. 60

65 When the car is moving to the left the con-

troller 19 on the left operates in the same manner its first and third sets of solenoids 15. My device therefore, as heretofore described, consists in the simultaneous advance of the controller in bringing the car 70 to speed, and the distribution of sand along the rails, which at the same time furnishes the proper adhesion to the wheels passing over the non-corrugated rail surfaces. According to my invention therefore, I am 75 enabled to supply automatically the proper amount of sand under each wheel of the car in which ever way the car may be moving, so that each wheel is properly supplied with sand requisite for adhesion, thus 80 doing away with the formation of corrugations by preventing the wheels slipping on the rails as the car is being brought to full speed.

I claim as my invention:—

1. The electromagnetic method of sanding rails to prevent and remove corrugations therein, which consists in supplying sand between progressing, rail-contacting revolving surfaces and said rails by means of, and in coördination with, the electric current employed substantially at all times during the acceleration of rotation of said revolving surfaces, so as to simultaneously furnish requisite adhesion between said surfaces and 90 rails to prevent the formation of corrugations, and to displace the crests of the corrugations already formed.

2. The electromagnetic method of sanding rails to prevent corrugations therein, which consists in supplying sand between progressing, rail-contacting revolving surfaces and said rails by means of, and in coördination with, the electric current employed substantially at all times during the acceleration of rotation of said revolving surfaces, so as to furnish requisite adhesion between said surfaces and said rails.

3. The electromagnetic method of sanding rails to remove corrugations therein, which consists in supplying sand between progressing, rail-contacting revolving surfaces and said rails by means of, and in coördination with, the electric current employed substantially at all times during the acceleration of rotation of said revolving surfaces, so as to displace the crests of the corrugations already formed.

4. An apparatus for sanding rails on electric railways, which comprises, in combination, a controller connected with the main circuit to operate the motors, a solenoid connected by successive contact points to the main circuit by the advance of the motor controller in starting and running positions, a sand box having an outlet to the rail, and a valve in said outlet connected with the solenoid to open the valve when the motor controller is advanced.

5. An apparatus for sanding rails on elec-

tric railways, which comprises, in combination, a controller connecting the motors to the main circuit, means to connect same in series or in parallel, a solenoid connected by successive contact points to the main circuit when the motor controller is advanced in starting and running positions, a sand box having an outlet to the rail, and a valve in said outlet connected with the sole-
5 noid to open said valve when the motor controller is advanced.

6. An apparatus for sanding rails on electric railways, which comprises, in combination, a controller connected with the main circuit to operate the motors, a solenoid connected to the main circuit by contact points in suitable relation with the advance of the controller in starting and running positions, a sand box having an outlet to the rail, and a valve in said outlet connected with the sole-
5 noid to open the valve when the controller is advanced.

7. An apparatus for sanding rails on electric railways, which comprises, in combination, a controller connected with the main circuit to operate the motors, means to connect same in series or in parallel, a solenoid connected to the main circuit by contact points in suitable relation with the advance
5 of the controller in starting and running positions, a sand box having an outlet to the rail, and a valve in said outlet connected with the solenoid to open the valve when the controller is advanced.

8. An apparatus for sanding rails on electric railways, which comprises a controller connecting the motors to the main circuit, means connecting same in series or in parallel, in combination with a sanding box having an outlet to the rail, a valve in said outlet, and means to automatically operate the sand valves with a suitable relation to the advance of the motor controller in starting and running positions.

9. An apparatus for sanding rails on electric railways, which comprises, in combination, a controller connected with the main circuit to operate the motors, an electromagnetic device connected by successive contact points to the main circuit by the advance of the motor controller in starting and running positions, and means for sup-

plying sand to the rails governed by said electromagnetic device when the motor controller is advanced.

55

10. An apparatus for sanding rails on electric railways, which comprises, in combination, a controller connecting the motors to the main circuit, means to connect same in series or in parallel, an electromagnetic device connected by successive contact points to the main circuit when the motor controller is advanced in starting and running positions, and means for supplying sand to the rails governed by said electromagnetic device when the motor controller is advanced.

60

11. An apparatus for sanding rails on electric railways, which comprises, in combination, a controller connected with the main circuit to operate the motors, an electromagnetic device connected to the main circuit by contact points in suitable relation with the advance of the controller in starting and running positions, and means for supplying sand to the rails governed by said electromagnetic device when the controller is advanced.

65

12. An apparatus for sanding rails on electric railways, which comprises, in combination, a controller connected with the main circuit to operate the motors, means to connect same in series or in parallel, an electromagnetic device connected to the main circuit by contact points in suitable relation with the advance of the controller in starting and running positions, and means for supplying sand to the rails governed by said electromagnetic device when the controller is advanced.

70

13. An apparatus for sanding rails on electric railways, which comprises a controller connecting the motors to the main circuit, means connecting same in series or in parallel, in combination with means for supplying sand to the rails, and means to automatically operate the sanding means with a suitable relation to the advance of the motor controller in starting and running positions.
